WARE.

SPEED-REGULATING DEVICE.

1,112,394.

Specification of Letters Patent.

Patented Sept. 29, 1914.

Application filed November 23, 1910. Serial No. 593,795.

To all whom it may concern:

Be it known that I, CARL G. SPRADO, a citizen of the United States, residing at Milwaukee, in the county of Milwaukee and State of Wisconsin, have invented a certain new and useful Improvement in Speed-Regulating Devices, of which the following is a specification.

This invention relates to improvements in the construction of predetermined speed regulating devices for rotating shafts, especially those of prime movers, such as steam turbines, gas engines, reciprocating steam engines, or other similar power generators. The object of the invention is to provide such a predetermined speed regulating device which is sensitive in its operation, thus permitting the speed of the shaft to be regulated within small limits to any predetermined speed.

A clear conception of one embodiment of the invention can be obtained by referring to the accompanying drawing which shows the regulating device applied to a steam-turbine as prime mover.

The single figure of the drawing is an elevation of the device partly in section.

The prime mover 1, which may be either a steam turbine, gas engine, reciprocating steam engine, or other rotary device, has a main shaft 14 to which an eccentric 15 is direct connected. The eccentric strap 18 on the eccentric 15, is adapted to reciprocate the piston 17 of a compressor or pump 16. The pump 16 is provided with suitable inlet valve 20 and discharge valve 21, which are shown diagrammatically as flap valves in the figure. The suction pipe 19 which enters the pump 16, leads from a suitable

source of fluid supply not shown. The high pressure discharge pipe 23 from the pump 16 has a T connection from which a branch pipe extends to the bottom of a high pressure reservoir 22. The top of the interior of the reservoir 22 constitutes an air chamber 33.

A second T connection in the high pressure pipe 23 provides for a branch pipe connecting to the interior chamber 13 formed in the regulator casing 8. The plunger or piston 12 carried at the lower end of the rod 10 is adapted to reciprocate within the casing 8 and is subjected to the pressure within the chamber 13. The spring 11 coats against the upper surface of the piston 12

and also against the lower surface of a cap which has screw thread coaction with the casing 8. The cap may be made adjustable so as to vary the compression in the spring 11 if so desired.

The upper end of the piston rod 10 is connected by means of a pivot 6 to one of the overhanging ends of the lever 7, having its fulcrum 4 on some stationary support. The opposite overhanging end of the lever 7 is connected to the upper end of the throttle valve stem 9 by means of a pivot 5. The lower end of the throttle valve stem 9 carries a throttle valve 3 which is adapted to control the admission of steam from the admission pipe 2 to the prime mover 1. The series of levers and rods connecting the piston rod 10 to the throttle valve 3, as shown, is a simple disclosure of one means of making this connection. However, this connection may lead to any device for varying the speed of the prime mover. Thus far described the control system contemplates inlet of fluid at a rate proportional to the speed of the prime mover. It is an essential feature of this invention to provide

other means contemplating outlet of the same fluid at a predetermined constant rate and any means for doing this might be used such, for instance, as a fluid meter running at a constant speed maintained so by pendulum control. The means illustrated herein for maintaining the predetermined constant outlet rate for the fluid is a constant orifice discharging the fluid at a substantially constant pressure. The specific means comprises a reducing valve delivering to a chamber discharging through an orifice.

The reducing valve 24, having the piston 26 therein, receives the pipe 23 at its high pressure end and discharges through a pipe connecting with the constant low pressure tank 28. The valve piston 26 is pressed downwardly by a spring 25, the compression of which spring is adjustable by means of a hand wheel 27 and screw. The piston 26 is free to rise and fall within a corresponding bore formed in the valve casing. It will be noted that with the construction of piston as shown, the pressure upon the bottom surface of the piston directly opposes the downward pressure of the spring 25 within the valve casing, since the high pressure acting upon the valve piston surfaces is balanced by acting upwardly and downwardly on

equal opposed areas at the top and bottom of the piston groove.

The low pressure reservoir 28, which is similar in construction to the reservoir 22, has a liquid therein which seals the lower end of the pipe entering the reservoir 28 from the reducing valve 24. The upper end of reservoir 28 constitutes a chamber 34. The outlet pipe near the lower end of the reservoir 28 connects with a needle valve 29. The valve 29 has a restricted orifice 31 which is under control of a hand operated needle 30, discharging therefrom to any suitable source, such as the supply tank from which the pipe 19 is fed.

It will be observed that the reducing valve 24, reservoir 28, and restricted orifice 31, constitute a means independent of the regulating device 8, for discharging pumped fluid at a predetermined constant rate, that is, the independence refers to the condition where the pressure in reservoir 28 differs from that acting on piston 12, or, the changing pressure acting on piston 12 is cut off 25 from the final delivery by the introduction of an independent or additional element. The fluid pressure variations due to load changes on the prime mover of the pump and regulating device 8, and the rate of flow of fluid past the draw-off point is 30 equalized.

During the operation of the device, the prime mover 1 causes the shaft 14 to rotate carrying with it the eccentric 15 and operating the compressor 16 through the eccentric strap 18. Fluid, preferably a liquid such as oil, is drawn into the pump 16 through the pipe 19 and is discharged from the pump 16 to the pipe 23, reservoir 22, chamber 13, and reducing valve 24. With the revolution of the shaft 14 constant, the quantity of oil pumped and its pressure will be constant and the piston 12 of the regulating device 8 will therefore be held in practically constant 45 position thereby maintaining a constant opening of the throttle valve 3. If for any reason the speed of the shaft 14 is changed, say increased, the pressure in the pipe 23, reservoir 22, and chamber 13 increases 50 to cause a greater quantity of oil is pumped and raises the piston 12 and piston rod 10. This raising of the piston 12 causes a corresponding lowering or closing of the throttle valve 3 and hence a resulting decrease to 55 slightly below normal in the speed of the prime mover 1. As the speed of the prime mover decreases, the pressure in the high pressure reservoir 22 and chamber 13 will immediately drop and the throttle valve 3 60 will be opened restoring the speed to normal.

Suppose the constant pressure on the low pressure side of the valve 24 to be 20 pounds absolute and the pressure in the high pressure reservoir 22 to vary from 40 to 80 pounds, 65 with the spring 25 set to exert a pressure

of 20 pounds per square inch on the cross section of the valve piston 26 when the valve has a position permitting flow at same rate as past needle valve 29; then as liquid under increased pressure passes the piston 26, the 70 pressure on the low pressure side of the system will, momentarily be raised a slight amount above the 20 pounds normally maintained, and overcoming the downward pressure of the spring 25 will immediately close 75 off more passage by the piston 26 by forcing the piston up into the bore of the valve casing. With the needle valve 29 open a certain amount, a constant flow of fluid will be maintained from the constant low pressure reservoir 28, a constant amount of fluid 80 will flow past the plunger 26 to replace the fluid discharged through the needle valve 29, because as the pressure momentarily increases the piston 26 cuts off the flow a proportionate amount.

Suppose it is desired to increase the speed of the prime mover a predetermined number of revolutions per minute. The orifice 31 of valve 29 is enlarged thus increasing the flow 90 from the low pressure reservoir 28 correspondingly. The pressure on the low pressure side of the system will then drop an amount proportional to the opening of the orifice 31, causing the spring 25 to open the 95 reducing valve 24. This will cause the pressure in the high pressure reservoir 22, pipe 23, and chamber 13 to decrease, resulting in a proportional increase of the speed of the prime mover 1 through the appropriate action of regulating device 8, lever 7, 100 and throttle valve 3.

The predetermined speed for any set position of the needle valve 29, however, will be constant, as above explained, an increase or decrease in speed of the shaft 14 from the predetermined speed resulting automatically in a corresponding increase or decrease in the pressure in the high pressure end of the device, which in turn acts directly to decrease 110 or increase the speed of the prime mover to the predetermined value. It will be noted that a secondary regulation of the speed of the prime mover may be had by adjusting the hand wheel 27. This adjustment, however, primarily affects the sensitiveness of the device. It will be less sensitive if the initial compression of the spring 25 is increased or if a heavier spring is used.

It should be understood that it is not desired to be limited to the exact details of construction shown and described, for obvious modifications will occur to a person skilled in the art.

It is claimed and desired to secure by Letters Patent,—

1. In a speed regulating device, a prime mover, a throttle valve for said prime mover, a pump driven by said prime mover, a high pressure system connected with the dis- 130

- charge of said pump, means actuated by the pressure in said system for controlling said throttle valve, a low pressure system, a reducing valve interposed between said high and low pressure systems, and means for drainage from said low pressure system at a predetermined constant rate.
2. In a speed regulating device, a prime mover, means for controlling the admission of working fluid to said prime mover, a pump driven by said prime mover and discharging to a high pressure system, means actuated by the pressure in said high pressure system for operating said controlling means, a low pressure system, a reducing valve interposed between said high and low pressure systems, and means for drainage from said low pressure system at a predetermined constant rate.
3. In a speed regulating device, a prime mover, means for controlling the admission of working fluid to said prime mover, a pump driven by said prime mover, a high pressure system receiving the discharge from said pump, means actuated by the pressure in said high pressure system to operate said controlling means, a low pressure system, a reducing valve interposed between said high and low pressure systems, and manually adjustable means for drainage from said low pressure system at a predetermined constant rate.
4. In a speed regulating device, a rotary element the speed whereof it is desired to maintain constant, means for restoring the speed of the element from any value deviating from said desired constant speed, fluid pressure actuated means controlling said speed restoring means, a pump driven by said rotary element for pumping said fluid, and means independent of said fluid pressure actuated means, for discharging said pumped fluid at a predetermined constant rate whereby the fluid pressure at the discharge differs from that acting on said fluid pressure actuated means.
5. In a speed regulating device, a prime mover the speed whereof it is desired to maintain constant when subjected to different loads, means for restoring the speed of said prime mover from any value deviating from said desired constant speed, fluid pres-
- sure actuated means controlling said restoring means, a pump driven by said prime mover for generating said fluid pressure, discharge means providing an orifice for discharging pumped fluid, said fluid pressure actuated means being interposed between said pump and said discharge means, and means preventing said fluid pressure from having direct access to the fluid being discharged past said orifice.
6. In a speed regulating device, a prime mover the speed whereof it is desired to maintain constant when subjected to different loads, means for restoring the speed of said prime mover from any value deviating from said constant speed, a pump driven by said prime mover, means subjected to fluid pressure generated by said pump for controlling said speed restoring means, and means for confining to the neighborhood of the pump, fluid pressure variations due to load changes on said prime mover and for equalizing the rate of flow of fluid at the draw-off point.
7. In a speed regulating device, a prime mover, a throttle valve controlling the admission of the working agent to said prime mover, a pump driven by said prime mover, means subjected to fluid pressure generated by said pump for controlling said throttle valve, and means including a pressure reducing valve for discharging said pumped fluid at a predetermined constant rate.
8. In a speed regulating device, a prime mover, a throttle valve controlling the admission of the working agent to said prime mover, a pump driven by said prime mover, means subjected to fluid pressure generated by said pump for controlling said throttle valve, and means including a pressure reducing valve for discharging said pumped fluid at a predetermined constant rate, and said fluid pressure subjected means being located on the high pressure side of said reducing valve.

In testimony whereof, I affix my signature in the presence of two witnesses.
